UNITED STATES PATENT OFFICE.

GEORGE W. DOVER, OF CRANSTON, RHODE ISLAND.

GEM-SETTING.

SPECIFICATION forming part of Letters Patent No. 717,824, dated January 6, 1903.

Application filed September 17, 1902. Serial No. 123,673. (No model.)

To all whom it may concern:

Be it known that I, GEORGE W. DOVER, a citizen of the United States, residing at Cranston, in the county of Providence and State of Rhode Island, have invented certain new and useful Improvements in Gem-Settings, of which the following is a specification.

My invention relates to gem-settings, and has for its purpose an improved means for retaining the setting-prongs against expansion. In another application, numbered serially 123,672, I have disclosed one means for attaining this end, and my present invention is designed as an improvement thereon. The particular structure therein shown is adapted exclusively for use in settings for flat-based gems, and the projections upon the arms of the supporting - planchet render the setting unavailable for use on some classes of jewelry.

To the ends above suggested my invention is as hereinafter set forth, and illustrated in the accompanying drawings.

Figure 1 is a perspective view of my novel retaining-ring; Fig. 2, a transverse central section of a setting provided with this ring; Fig. 3, a planchet adapted to be bent up into a setting; Fig. 4, a completed setting; Fig. 5, a transverse central section of a complete setting embodying my invention applied to a gem with a conical or pyramidal base, and Fig. 6 a detail of an unbent arm used with conical gems.

Like letters of reference indicate like parts throughout the views.

My setting is constructed as follows: A planchet B is struck or cut from a sheet of metal consisting of a body portion a and radial arms b. The latter are provided with lateral shoulders c, intermediate which rise

points d. On either side of the bases of the 40 points d and extending into the shoulders are slots o. The shoulders c of each arm are next bent inwardly parallel to each other, as shown by one of the arms in Fig. 3. The arms are then bent upwardly into final position. I 45 then insert a ring A, Fig. 1, in the slots o of the shoulders c of the prongs and upon this place the gem, after which the points d are bent over the edge of the gem.

It is evident that the so-called "ring" A 50 may be polygonal as well as annular, and its contour may contain irregularities, without departing from the spirit of my invention, and it is with this interpretation that the word "ring" is employed for this member. 55

When a conical or pyramidal based gem is used, the planchet-arm has its shoulders diagonally cut, as shown in Fig. 6.

Having thus described my invention, what I claim is—

1. In a gem-setting the combination with the setting-prongs of shoulders upon the prongs, slots in said shoulders, and a ring resting in said slots.

2. In a gem-setting the combination with 65 the setting-prongs, of shoulders upon the prongs, slots in said shoulders, a ring resting in said slots and a gem engaged by said prongs.

3. In a gem-setting the combination with 70 the setting-prongs, of recesses in said prongs, and a ring resting in said recesses.

In testimony whereof I have affixed my signature in presence of two witnesses.

GEORGE W. DOVER.

Witnesses:

HORATIO E. BELLOWES,
FENNER JACKSON.
